(57) **CLAIM**

The ornamental design for a training device, as shown and described.

DESCRIPTION

FIG. 1 is a perspective view showing our new design; FIG. 2 is a first side elevation view thereof;

FIG. 3 is a second side elevation view thereof; and

FIG. 4 is a front elevation view thereof;

FIG. 5 is a rear elevation view thereof;

FIG. 6 is a top plan view thereof;

FIG. 7 is a bottom plan view thereof.

FIG. 8 is an alternative front elevation view with broken line environment;

FIG. 9 is another alternative front elevation view with alternative broken line environment; and,

FIG. 10 is another bottom plan view thereof with additional broken line environment.

The broken lines shown in the drawings represent environment and portions of the article that form no part of the claimed design.

1 Claim, 10 Drawing Sheets
